UNITED STATES PATENT OFFICE.

WILLIAM A. FRANK, OF HACKENSACK, NEW JERSEY, ASSIGNOR TO NATIONAL WATER MAIN CLEANING COMPANY, OF NEW YORK, N. Y., A CORPORATION OF MAINE.

PIPE-CLEANER.

1,193,005.

Specification of Letters Patent.

Patented Aug. 1, 1916.

Application filed January 13, 1915. Serial No. 1,924.

To all whom it may concern:

Be it known that I, WILLIAM A. FRANK, a citizen of the United States of America, residing at Hackensack, in the county of Bergen and State of New Jersey, have invented certain new and useful Improvements in Pipe-Cleaners, of which the following is a specification.

The present invention relates to an improved apparatus for cleaning pipe lines or water mains and is particularly concerned with that type of device which employs what are generally termed "scrapers," the function of which is to loosen and remove from the inner walls of the pipe the sediment or incrustation which forms thereon after a longer or shorter period of use.

In this class of pipe cleaners it is usual to employ a number of scraper heads arranged in succession, each head being provided with a set of scrapers all of which are adapted to act on the sediment or incrustation in the pipe.

It has heretofore been customary to mount the scraper heads directly on a shaft, and with this construction the entire weight of the machine was usually borne by the scrapers in the lowermost position, that is, those scrapers which were acting on what might be termed the base of the pipe. This condition involves a number of disadvantages.

In the first place, the scraping action of the upper scrapers is likely to be less effective than that of the lower scrapers owing to the fact that such upper scrapers are pressed against the pipe with less force than the lower scrapers which carry the weight of the machine. Again, the weight of the machine borne on the lower scrapers acts as a drag to retard the passage of the cleaning machine through the pipes. Furthermore, the pressure of the machine on the scrapers has the effect of dulling the scraper edges rapidly and bending the scrapers out of shape.

One object of my invention is to provide a construction of cleaning device in which the entire series of scrapers is firmly, yet flexibly supported free of the shaft, so that those scrapers which at any time happen to be the bottom scrapers are subjected to but little greater pressure than any of the other scrapers of the series.

In prior scraper constructions, some difficulty has also been experienced in so securing the scrapers proper to the scraper carry-

ing heads as to prevent the scrapers from working loose from the supporting heads.

Another object of my invention is to so construct the device that the scrapers will be firmly, yet removably, held in position on the scraper head, to eliminate the danger of any of the scrapers becoming detached from the scraper head while the latter is in the pipe being cleaned.

Another object of the invention is to provide a novel arrangement of scraper blades, whereby I am enabled to provide each scraper head with a greater number of blades than heretofore.

A still further object of my invention is to provide such a device with means whereby a gradual rotating or turning movement will be imparted thereto, so as to coöperate in attaining the desired maximum cleaning efficiency. The means for imparting the turning movement are preferably constructed to be capable of participating in the cleaning action of the scrapers.

The construction and operation of the invention will be clearly understood from the following detail description taken in connection with the accompanying drawing, in which—

Figure 1 is a longitudinal sectional view of a pipe or water main, showing my improved cleaning apparatus therein, a portion of the latter appearing in section; and Fig. 2 is a cross sectional view on the line 2—2 of Fig. 1.

The specific type of device shown in the drawing is one which is propelled through the pipe by the pressure of the water acting on pistons having adjusting means to regulate the quantity of water which may pass the pistons so as to vary the speed at which the device advances through a main. It will be understood, however, that my invention is not limited to any particular means for advancing the cleaner through the pipe, but may be employed in connection with any approved means for this purpose.

In the drawing, numeral 10 denotes the water main which it is assumed has interior incrustation to be removed by my improved apparatus.

I will now describe the construction of the cleaning apparatus itself. 11 denotes a shaft section upon which a series of cleaner heads or scraper-supports 12 are mounted. Each head is substantially cup-shaped with

a relatively large aperture 13 in its base or front wall, the shaft 11 passing through and preferably clearing the walls of the apertures in the heads 12. The shaft 11 has 5 keyed or otherwise attached to its forward end a guide head 14 provided with a series of radiating arms 15, which are bifurcated for the purpose of supporting guide wheels 16 on stud shafts 24. These wheels 16 are 10 revolvable in the bifurcated arms 15 and are set thereon so as to incline with relation to the axis of the pipe 10, or the shaft 11, which as will be understood are co-axial when the device is in operation. By so inclining the 15 guide wheels 16 with relation to the axes of the pipe 10 and shaft 11, the entire device, as it advances through the pipe, is given a rotary or turning movement which conduces to subjecting all parts of the interior of a 20 pipe to the action of the scrapers, to be presently described. It will also be noted that the edges or peripheries (Fig. 2) of the guide wheel 16 are sharp, almost forming knife edges. This construction has a two-fold object. Owing to the sharp edges of 25 the wheels the resistance to the advance of the device through the pipe is reduced compared to what it would be if the peripheries of the guide wheels 16 were wide, and furthermore, the sharp edges of the guide 30 wheels act to some extent in scarifying the incrustation and rendering its removal somewhat easier by the succeeding action of the scrapers.

35 The scraper members usually comprise steel blades 17, curved outwardly at one end and provided with widened scraping ends or edges 18, which act on the incrustation in the pipe. The end opposite 18 is adapted to 40 be held in the scraper head 12, and for that purpose such end is preferably made angular in cross section so that the portion 17a thereof may pass through an aperture in the lateral wall of the head or cup 12, while 45 the inner end or portion 19 of the blade or scraper may abut against the inner face of the base wall of the cup or scraper head. By the construction described, accidental detachment of the scraper blades from the 50 scraper heads is prevented, inasmuch as the angular portion 17a of the blade bears against opposed stop surfaces (the walls of the aperture in the lateral wall of the cup) and at its rear end each such blade also 55 abuts against a stop surface, formed by the base wall of the cup. As an additional safeguard against accidental detachment of the blades, I provide the bolts 20 which pass through the blade shanks and into and 60 through the lateral walls of the cups 12.

A desirable feature of my present construction is the arrangement of the blades on the scraper heads. It has been found, in practice, that to obtain satisfactory results 65 it is necessary to employ a considerable num-

ber of scraper blades, which are to act on the pipe incrustation. Economy of construction and operation requires that the number of scraper heads employed shall be as few as possible, consistent with efficiency. To meet 70 these conditions, I preferably arrange the blades in staggered relation to each other on the scraper heads, whereby I am enabled to provide each scraper head with a greater number of blades than if the latter were 75 placed side by side in alinement. The fifth scraper head in Fig. 1 clearly illustrates the staggered arrangement of blades; the cutting edges 18 of two spaced blades being overlapped by the cutting edge of an intermediate blade. When a scraper head, with blades so arranged, passes through a pipe, practically the entire inner surface of a given portion of the latter will be acted upon by the ring or series of blades. 85

To obtain effective cleaning action, it is customary and desirable to employ at least two sections of shafts 11 each with scrapers thereon, and in Fig. 1 of the drawing I have shown a scraper unit as comprising two 90 shaft sections 11, the first section including three scraper heads and the second section including two scraper heads and piston propulsion means which will be later described.

In order that the shaft sections may be 95 suitably connected together, the forward end or guide head 14 of each shaft 11 is provided with a socket 21 into which is adapted to fit a ball 22 carried at the rear of each shaft 11, forming a ball and socket joint 100 suitably united by the bolted frame 23.

I have found, in practice, that the most desirable manner of flexibly supporting the scraper heads is to connect them by chains to the guide head 14. Hung on the stud 105 shaft 24 of each wheel 16 is a link 25 engaged by one end of a chain 26 which passes through the aperture 13 in the heads 12 forming the scraper series. To the outer face of the base wall of each scraper head 110 12 is riveted or otherwise attached a series of metallic eyes 27 each of which is engaged by a link 28, said links being connected to the chain 26. As will be noted from Fig. 1, the chain does not pass through 115 aperture 13 in the last head 12, but merely has its end attached to the eye 27 on the base wall of this head. The chains 26 are arranged to form a circle or substantially cylindrical series, there being as many 120 chains 26 as there are wheels 16 whereby the supporting action of these chains is practically uniform throughout the entire circumference of the scraper heads 12. The flexible support afforded by the chains 26 with 125 the aid of the piston propulsion means hereinafter described, is sufficient to keep the scraper heads centered throughout the series, and to allow any scraper head to yield if this becomes necessary by a substantial ob- 130

struction to its forward passage through a pipe or around bends.

To prevent the several scraper heads from working forward out of place, each shaft 11 has attached thereto a number of plates 29, the diameter of which is greater than that of the aperture 13 in the heads 12. These plates are positioned adjacent the heads 12 and act as stops to the forward movement on the shaft 11 of the heads 12. The plates are suitably orificed to allow the chains 26 to pass therethrough.

Mounted on the shaft of each cleaning unit (two or more sections) is a pair of flexible pistons each of which comprises an inner casing 30 of leather or like tough material and a series of outer spring arms 31, engaging the leather casing 30 and adapted to protect the same against abrasion. To maintain the flexible sheathing 30 in distended position is an annular coiled or spiral spring 32 which presses against the inner ends of the arms 31, the latter being preferably lapped over the lower edge of the casing 30, as shown in Fig. 1.

Secured to the shaft 11 is a disk 33 forming a clamp to retain the flexible sheathing 30 and the arms 31 in position. This disk is provided with apertures 34, and revoluble over the disk is a plate 35 having spaced webs 35^a so that by revolution of the plate 35 the spaces between the webs thereof may be brought into and out of register with the apertures in the disk 33. The action is somewhat in the nature of a damper or valve action, the apertures being adjustable in size so as to permit a greater or less quantity of water to flow therethrough and thus to regulate the speed at which the device is advanced through the pipe by means of the piston above described.

It is to be noted that the pistons at the rear of a scraper unit are attached to the shaft 11 and thus assist in centering the shaft, from the guide heads of which the scraper heads are flexibly supported by the chain construction above described.

The operation of the device will be understood from the following description. Before the device is placed in the pipe to be cleaned, the plates 33 and 35 are adjusted relatively to each other so as to provide apertures of a size which will control the speed of advance of the cleaning device as desired. After such adjustment of apertures the device is placed in a pipe with the guide heads 14 pointed in the direction in which the device is to travel. Thereafter the water is turned on and as it flows it will advance the cleaning device, which will be rotated owing to the action of the wheels 16. As the cleaner advances the sharp edges of the wheels 16 will scarify the incrustation on the interior of the pipe, such incrustation being removed by the successive

action of the edges 18 of the scraper blades 17.

What I claim as new and desire to secure by Letters Patent is:—

1. A pipe cleaning machine, embodying 70 therein a shaft having a guide head, a series of scraper heads, and means for supporting said scraper heads from the guide head free of said shaft.

2. A pipe cleaning machine, embodying 75 therein a shaft having a guide head, a series of scraper heads, and flexible means for supporting said scraper heads free of said shaft.

3. A pipe cleaning machine, comprising 80 a shaft provided with a guide head, means carried by said guide head for guiding the device and rotating same in its passage through a pipe, scraper heads, and means secured to said guide head and by which 85 said scraper heads are supported free of the shaft.

4. A pipe cleaning machine, comprising a shaft, a series of scraper heads having apertured walls through which said shaft 90 extends, and means attached to said guide head for supporting said scraper heads independently of the shaft.

5. A pipe cleaning machine, comprising 95 a shaft, a guide head thereon, a series of revoluble guides carried by said guide head, a series of scraper heads through which said shaft passes, and means connected to said guide head and to said scraper heads for supporting the latter independently of said 100 shaft.

6. A pipe cleaning machine, comprising a shaft, a guide head at one end thereof, a series of sharp edged guide wheels carried by said guide head, scraper heads through 105 which said shaft passes, and flexible means connected to said guide head and to said scraper heads for supporting the latter independently of the shaft.

7. A pipe cleaning machine, comprising 110 a shaft, a guide head at one end thereof, a series of sharp guide wheels carried by said guide head, said guide wheels being inclined with respect to the axis of said shaft, and a series of scraper heads, supported from said 115 guide head free of said shaft.

8. A pipe cleaning machine, comprising a shaft having a guide head thereon, revoluble guiding members carried by said guide head, a series of scraper heads through which said 120 shaft passes, and chains connected to said guide head for sustaining said scraper heads independently of said shaft.

9. A pipe cleaning machine, comprising a 125 scraper head consisting of a substantially cup-shaped member having a base wall and a lateral wall, and scrapers passing through apertures in a wall of said scraper head.

10. A pipe cleaning machine, comprising a scraper head having walls at an angle to 130

each other, at least one of which walls is provided with apertures, and scrapers passing through said apertures.

11. A pipe cleaning machine, comprising a scraper head consisting of a substantially cup-shaped member having walls at right angles to each other, each of said walls being provided with an aperture, and a scraper having a substantially rectangular portion 10 passing through the apertures in said walls.

12. A pipe cleaning machine, comprising a shaft carrying a guide head at one end thereof, means on said guide head whereby said machine may be guided and rotated in 15 its passage through a pipe being cleaned, scraper heads flexibly supported from said guide head free of the shaft, and means whereby said device may be advanced through a pipe by water flowing there- 20

25 13. A pipe cleaning machine, comprising a shaft having a guide head thereon, a series of sharp edged wheels carried by said guide head said wheels being inclined with respect to the axis of said shaft, a series of scraper heads arranged in succession behind said guide head, and flexible means whereby said scraper heads are supported free of said shaft.

30 14. A pipe cleaning machine, comprising a shaft having a guide head at one end thereof, a series of scraper heads in succession to the rear of said guide head, each of said scraper heads having an aperture in its base through which said shaft passes, and a series of chains connected to said guide heads and said scraper heads, and passing through the apertures in the bases of the latter.

35 15. A pipe cleaning machine, comprising a shaft, a series of scraper heads through

which said shaft passes, means for flexibly supporting said heads free of the shaft, and means for maintaining a predetermined distance between said heads. 45

16. A pipe cleaning machine, comprising a shaft, a series of scraper heads through which said shaft passes, means for flexibly supporting said heads free of the shaft, and plates on the shaft for maintaining a pre- 50 determined distance between said heads.

17. A pipe cleaning machine, comprising a shaft, a series of scraper heads flexibly supported clear of the shaft, a series of perforated plates on the shaft adjacent said 55 heads, and chains passing through said plates and connected to said heads for flexibly supporting the latter clear of the shaft.

18. A pipe cleaning machine, comprising a shaft, a guide head thereon, a series of 60 scraper heads flexibly supported from said guide head free of said shaft, and a piston by means of which said machine may be advanced through a pipe, said piston including a flexible casing and resilient means for 65 distending the same.

19. A pipe cleaning machine, comprising a shaft, a guide head thereon, a series of scraper heads flexibly supported from said 70 guide head free of said shaft, and a piston by means of which said machine may be advanced through a pipe, said piston including a flexible casing, resilient means for distending the same, and metallic means for protecting said casing against abrasion. 75

In testimony whereof I have affixed my signature in presence of two witnesses.

WILLIAM A. FRANK.
